INVENTOR,
Thomas Pattison,

BY Francis M. Wright
ATTORNEY

UNITED STATES PATENT OFFICE.

THOMAS PATTISON, OF SANTA CLARA, CALIFORNIA.

CAR-VENTILATOR.

1,205,475.

Specification of Letters Patent. Patented Nov. 21, 1916.

Application filed April 12, 1915. Serial No. 20,712.

To all whom it may concern:

Be it known that I, THOMAS PATTISON, a citizen of the United States, residing at Sunnyvale, in the county of Santa Clara and State of California, have invented new and useful Improvements in Car-Ventilators, of which the following is a specification.

The object of the present invention is to provide an improved ventilator for street and railroad cars.

In the accompanying drawing, Figure 1 is a front view of the ventilator in position on a car, part of the roof of the car being shown in section; Fig. 2 is a longitudinal section 15 of the same on the line 2--2 of Fig. 1; Fig. 3 is a longitudinal section of a portion of the ventilator; Fig. 4 is an end view of an upper portion of the ventilator.

Referring to the drawing, 1 indicates the roof of a car, into a rectangular hole in which are inserted, with a snug fit, side walls 2 and end walls 3 depending from the central portion of the lower section 4 of my improved ventilator, which lower section thus forms a rectangular flue or chimney and may be termed the ventilator proper, the upper section being merely the protecting hood or cover therefor. Said side walls 2 have near the top two long, 25 narrow horizontally extending holes 5, and with each side wall are connected, on opposite sides of the hole 5 therein, downwardly and outwardly extending oblique walls 6, 7, diverging from each other outward, the slope of the lower portions of said walls being considerably less than that of their upper portions. The ends of said walls are connected to the edges of extensions 8 of the end walls 3, said walls 6, 7, thus forming, with said extensions, on each side of the flue or chimney, a chamber or conduit 9 having a wide lower open end and a narrow upper open end. Each conduit is divided midway into compartments by a 45 partition 11, which has the same general direction as the upper and lower walls 6, 7 of the conduit. Since the lower open ends of these chambers face to the front and rear of the car respectively, it follows that, 50 when the car is in motion, air is pressed into the forward conduit 9 with a force corresponding to the speed of the car, and, by reason of the walls 6, 11 and 7 of the conduit converging, the pressure of the air 55 entering said conduit 9 gradually increases, so that the air issues from the upper nar-

row open end of the conduit with great velocity. This narrow stream of air, directed upward with great velocity in the vertical flue or chimney 4, has the effect of 60 creating an upward draft in said flue, and of thus drawing off and expelling the air from the top of the interior of the car.

I also provide a vertical partition 10 midway between the two side walls 2 of the lower section, the ends of which are secured to the end walls 3 of said section. This partition serves a very important purpose, for, but for the partition, the stream of air flowing with great velocity through the conduits 9 on one side and leading to the points immediately above the inlet mouths of the conduits 9 on the other side would produce an upward suction in said latter conduits, and thereby a considerable portion of the 75 energy of said streams of air would be used without performing useful work in drawing the air upward through the ventilator flue. By interposing the partition 10, which prevents said streams of air reaching the 80 inlet mouths of the opposite conduits 9, this result is avoided.

I also provide improved means for preventing rain, sleet or snow from entering the car through said flue 4. For this purpose there is provided a comparatively large horizontally extending open-ended pipe 13, having a longitudinal rectangular opening therein, and having walls 14 depending from the pipe around said opening, said opening being of such size that said walls can fit snugly around the upper portion of the flue 4, said pipe 13 thus forming a hood. When the hood is in position upon the ventilator proper, the stream of air flowing upwardly 90 thereinto from said flue flows to each end of the pipe 13. Fitting around each open end of the pipe is a ring 16, to which are connected the inner edges of plates 17, of which the outer edges are connected to a large ring 19, each end 21 of which converges 95 conically. To the outer ends of said plates are also connected circular disks 22.

The ends of each ring 19 are spaced respectively from the adjacent open end of the pipe 13 and the edge of the adjacent disk 22, so that the air can freely pass therebetween. Also each disk 22 has therein a large opening 23 to permit the air to pass therethrough, and, in order to prevent the 105 entrance of rain, sleet or snow through said opening 23, there are secured to each disk 110

22, around the opening 23, the feet 24 of legs 26 secured to a protecting cover plate 27, said plate 27 being spaced from the adjacent disk 22 sufficiently to permit the passage of air therebetween.

It will be seen that, with this construction the egress of air from the flue 4 and pipe 13 is greatly facilitated. At the same time rain is prevented from entering the 10 flue on account of the protecting covers 27, and also on account of the ends of the rings 19 being conical and extending over the ends of the pipe 13. Should, however, any rain enter either end of the hood, its progress will be arrested by a channel 28 in the ring 19, from which it can escape by holes 29 provided for that purpose, and will also be arrested by channels 30, 31, in each end of the pipe 13.

20 It will thus be seen that I provide positive means for drawing off the impure air from the interior of the car, requiring no power for operating the same other than the movement of the car itself, and said 25 means being well adapted to exclude the entrance of rain, sleet or snow. To provide against the entrance of snow through the conduit 9, I provide doors 32, which, as shown in Fig. 2, may be closed when desired.

I am aware that it has been proposed to draw air downward out of a car by means of a rearwardly and downwardly directed conduit uniting with the bottom of a vertical exhaust passage, but I have found that it is essential for the best results that the 35

rearwardly directed conduit should be connected at its rear end with the exhaust passage at a point where the exhaust air from the car is still inclosed by the walls of the 40 exhaust passage. If the rearwardly extending conduit joins the exhaust passage where it communicates with the outside atmosphere, it does not have the same effect of producing an upward or downward draft, 45 as the case may be, in the exhaust passage as when it enters said exhaust passage at an intermediate point thereof where the exhaust air is still confined in the passage. The reason for this is that the rearward 50 stream of air flows across the end of the passage instead of being directed upwardly or downwardly by the walls of the passage.

I claim:—

In a car ventilator, the combination of a 55 flue leading upwardly from the inside to the outside of the car, a conduit leading rearwardly from the outside of the car to an intermediate point of the flue and directed upwardly at its rear end, a transversely extending pipe open at both ends 60 into which said flue discharges at the top and means for preventing the entrance of rain or the like into said pipe.

In testimony whereof I have hereunto set 65 my hand in the presence of two subscribing witnesses.

THOMAS PATTISON:
